UNITED STATES PATENT OFFICE.

GEORGE W. COPE, OF DETROIT, ASSIGNOR TO HUGH L. SMITH, OF JACKSON,
MICHIGAN.

DESIGN FOR AN OIL-STOVE.

SPECIFICATION forming part of Design No. 22,371, dated April 25, 1893.

Application filed January 28, 1893. Serial No. 460,163. Term of patent 3½ years.

To all whom it may concern:

Be it known that I, GEORGE W. COPE, a citizen of the United States, residing at Detroit, in the county of Wayne and State of Michigan, have invented and produced a new and original Design for an Oil-Stove, of which the following is a specification, reference being had to the accompanying drawings, in which—

Figure 1 is a front elevation of an oil stove showing my design. Fig. 2 is a side elevation thereof, and Fig. 3 is a plan.

The design consists of the shape of the body, having a rounded back C, and flat front D, formed with an ornamental swell bay E extend-

ing up to a point near the top. This body 15 has the flat base A and legs B. On the upper end of the body is the ornamental curved and inclined cap G having an ornamental edging H, which is inclined slightly toward the rear. 20

What I claim is—

The design for an oil stove, substantially as herein described and shown.

GEORGE W. COPE.
